UNITED STATES PATENT OFFICE.

SAMUEL DUNCAN BLACK AND ALONZO GALLOWAY DECKER, OF BALTIMORE, MARYLAND, ASSIGNEES, BY MESNE ASSIGNMENTS, TO THE MARYLAND TRUST COMPANY, TRUSTEE, A CORPORATION OF MARYLAND.

PUMPING APPARATUS.

Application filed July 23, 1919. Serial No. 312,784.

To all whom it may concern:

Be it known that we, SAMUEL DUNCAN BLACK and ALONZO G. DECKER, citizens of the United States of America, and residents of the city of Baltimore, State of Maryland, have invented certain new and useful Improvements in Pumping Apparatus, of which the following is a specification.

The subject of this invention is a pumping apparatus with motor, pump, gearing, and in fact the entire apparatus complete in a single casing.

Important features of the invention are found in the arrangement of the different units making up the apparatus, in the manner of mounting the same within the casing itself and in the combination of these features to effect cooling, utilizing the casing as an air jacket for cooling both the motor and the compressor cylinder.

The cooling effect which is achieved in this way is so effective that the motor may without injury be driven at a high speed far in excess of the speed of which the same motor would be capable with the same load if uncovered. It is therefore geared for such a speed and under these conditions it develops a proportionately larger horse power, making it possible to use a smaller motor than when the apparatus is differently arranged, thus reducing the bulk and cost of the apparatus without loss of efficiency.

Otherwise, the arrangement of the parts in a single casing in accordance with the present invention protects the parts from dirt, grit and the action of the elements, and from breakage, gives a pleasing appearance and protects those in the vicinity from injury by contact with the gears and other moving members.

In the use of compressed air for various purposes, particularly in the inflation of tires, complete absence of oil from the compressed air is essential, and the greatest permanency of the lubrication is highly desirable, making it possible to close the casing and give no attention to the apparatus for long periods of hard service. The present device includes a lubricating system particularly adapted for use in this connection in that it uses heavy grease as a lubricating agent for the connecting rod and wrist pin bearing and in the cylinder, the grease be-

ing applied to the cylinder in very small quantities by a system which supplies such small quantities of grease with the greatest regularity, the difficulty of achieving uniform distribution of such grease being the principal obstacle to its use. To accomplish this a supply of the proper kind of heavy lubricant which is of about the consistency of vaseline is placed in the crank case so that the crank dips into it at every revolution. The bottom of the cylinder just beneath the piston is closed by means of a sheet or disk of absorbent material shown as felt. This is slotted to pass the connecting rod and is just high enough to be engaged or struck by the bottom surface of the piston at each stroke of the pump. The heavy grease works up along the connecting rod and is thrown up sufficiently to keep the bottom surface of the felt disk smeared with grease. This works through the disk by capillarity or otherwise, and small quantities are transferred to the piston at each stroke, the contacting surfaces of the piston and cylinder being lubricated by the portion of the grease that works by and over the edges of the piston. The shaft bearings are also lubricated with hard grease, evenly and regularly applied as hereinafter described.

This mode of lubrication prevents absolutely the introduction of grease into the compressed air and is beneficial and economical as the hard grease is a most efficient lubricant. Fully supplied with this lubricant, the apparatus will run without attention as to lubrication for many months, and is very economical in the expenditure of grease.

Another important feature of the invention consists in the construction of the casing or housing in two sections, the lower section somewhat resembling in shape an ordinary bath tub or dish with the parts bridged across the top of the casing, the latter acting as a support.

In the accompanying drawing we have illustrated the commercial form of pumping apparatus embodying the features of our invention in the preferred form.

In the drawings—

Figure 1 is a vertical central longitudinal section, certain parts being shown in elevation.

Figure 2 is a section on the line 2, 2 of Figure 1 looking toward the motor, the same being on a plane transverse to the plane of Figure 1.

5 Figure 3 is a section on the line 3, 3 of Figure 1 in a plane parallel with Figure 2, the plane of the figure being the plane of the axis of the pump cylinder.

10 Figure 4 is a section on the line 4, 4 of Figure 1 taken on a plane transverse to the plane of Figure 1 and showing the fan and adjacent portion of the casing.

15 Figure 5 is an external view, particularly an end elevation, taken from the right of the machine as seen in Figure 1.

Referring to the drawings by numerals, the apparatus consists of a housing 1 enclosing and supporting a pump 2, an electric motor 3, suitable gearing 4 connecting the 20 motor and pump, and a fan 5 on the motor shaft. More particularly, the casing in its preferred form as shown is divided horizontally into a bottom section 7 having suitable baffles and bearing supports as hereinabove described, and a top section 8 which is 25 shown as constructed in three parts connected by a lap-joint 9 and 9'. The top section is also illustrated as provided with an upright turret 10 for the pump cylinder 11, 30 the head of which protrudes from the casing as indicated at 12 and to be hereinafter further described. The bottom half of the casing 7 is provided at each side near the top with inwardly projecting ears 13, 14, 15, 16, 35 117 and 118. The ears 13, 14 at the front, i. e., adjacent the cylinder turret 10, serve as a support for the pump cylinder base 17 which is bridged across the casing at this 40 point overlying the ears 13, 14 at each side and bolted thereto. Further back the motor frame 18 is bridged across the casing resting on and being bolted to the ears 15 and 16.

Between the pump and the motor the bottom section is divided by a transverse partition 19 supporting a bearing boss 20 for the 45 crank shaft 21. The bearing contains a bushing 22. Above the bearing the partition 19 is formed into a transverse channel or trough 23 containing lubricant preferably in the form of heavy grease. The bottom 230 of the channel or receptacle 23 is inclined downward toward the center as shown in Figure 3, and at this point there is an aperture 231 suitably curved as to its bottom or outer surface as indicated in dotted lines in Figure 3, the curve being almost tangent to the curve of the inner surface of the bearing and shaft surface but intersecting them to a slight degree. This aperture extends through 50 the bushing 22 to the bearing surface and shaft, a considerable area of which shaft is exposed as indicated. In the aperture 230 is a portion of a wick 232, the same being 55 pressed downward into the aperture by a plate spring 233, the remote end of the spring

and the wick being secured to the bottom of the channel by a bolt or screw 234. It will be noted that the wick conforms to the surface of the aperture and bears against the exposed surface of the shaft.

It becomes and remains thoroughly saturated with grease which oozes through the wick fabric in sufficient quantities to keep the shaft bearing lubricated without supplying any surplus which might leak out between the bearing surfaces and be wasted or carried over with the air.

Above the partition 19 the casing is spanned by a strut or bearing support 24 carrying a bearing 241 for the motor shaft 25. This strut 24 has a depending web 242 which overlaps the top edge of the partition 19, and the overlapping portions are shown as packed with a strip of fibrous material of felt 26.

It will be noted that the overlapping edges are in the form shown inclined downward toward the center of the casing to accommodate the bearing. The bearing 241 which has a bushing 243 is apertured from beneath as indicated at 244, the aperture being formed on a shallow curve in a plane transverse to the axis of the shaft, which curve is nearly tangent to the shaft, the bushing being cut away to provide a considerable opening at 245 exposing a section of the shaft. The aperture is occupied by the end portion of a wick 250 which dips in the lubricant in the receptacle 23, the wick being in turn held in position in the aperture by means of a plate spring 246.

The channel or receptacle 23 being supplied with heavy grease, the wicks remain saturated with the grease, and the bearings are thus evenly and continually coated with heavy lubricant. While this has the advantage of adhering to the lubricated parts so that it is not carried over with the air, it also is of a more permanent nature than the lighter lubricating oils and is much more efficient as a lubricant. A lubricant of this nature is more dependable and lasts longer than lighter oil. The bearings thus lubricated need no attention except at periods of 110 several months nearly constant or continual running.

Referring to Figures 1 and 4, it will be noted that there is a partition 28, partly longitudinal or otherwise offset from the partition 19 and otherwise extending transversely of the casing as indicated. In the plane of this partition and co-operating therewith is a partition 29 in the top half of the casing 8. The partitions 28 and 29 are pierced by a circular aperture 30, half in one and half in the other and formed concentric with the shaft 25 of the motor. While the offset or shoulder 31 referred to as the longitudinal portion of partition 28 is 125 drawn on a curve which at the right in 130

Figure 4 is concentric with the shaft 25, on the left it is of increasing radius which meets the casing at the top edge, giving a formation corresponding to the usual blower 5 housing.

The rear half of the lower section which may be termed the motor casing, is further divided by a transverse partition 33, see Figure 2, on the central transverse plane of the 10 motor. This partition serves as a web or strengthening member extending from the lug 15 which supports the motor on one side to the lug 16 which supports the motor on the other side, being formed integrally with 15 the walls of the bottom half of the casing on the entire section and curved to enclose the motor frame. It is also cut away centrally at 34 to admit the crank shaft 21.

The crank shaft 21 is supported at the rear 20 in a bearing boss 35 having a suitable bushing 36 and formed above into a grease cup 37 from which grease is fed to the bearing surface by a spring controlled wick 38. The bearing has a cover 39 held in position by 25 a spiral spring 40 which passes around the boss and is hooked at each end into the cover 39. The shaft 21 is held in position against end play by a washer or disk 42.

The motor shaft is mounted in the bearing 30 member 241 already described, back of which bearing member is the fan 5 also carried on this shaft. Beyond the fan is the motor 3 and the rear end of the shaft is carried in a suitable bearing boss 47 on a transverse strut 35 46 secured to the frame on suitable ears 117 and 118 at each side. This bearing boss is bushed as shown and provided at the top with a grease cup 48 from which grease is led to the bearing by a wick 49 as in connection 40 with the grease cup 37.

At the forward end of the crank shaft is the fly-wheel or crank disk 43 secured to the shaft by suitable means as a taper fit, key and nut 44. This crank disk member is 45 toothed on its periphery at 45, the teeth meshing with the teeth of a pinion 146 on the motor shaft by which the crank or fly-wheel member is driven.

The crank disk 43 carries a crank pin 50 which as shown is hollow for purposes of lubrication, having radial passages 51. This pin engages a suitable bearing 52 in the end 55 of the connecting rod 53, the bearing being provided with a lubricating passage 54 to co-operate with the passages 51.

The pump as shown has a single upright cylinder 11 supported in the turret 10 of the top half of the casing as already described, the same being mounted on a base 60 17. In this cylinder is the piston 55 actuated by a connecting rod 53 through the usual wrist pin 56.

The lubrication of air pumps has been a difficult problem on account of the necessity 65 for keeping the compressed air free from oil.

This is accomplished in the present instance by using a heavy grease distributed as follows. The bottom of the cylinder in the form of the invention shown, is closed by a fibrous or felt pad or disk 57, the same being in the 70 form of the invention shown supported by a thin metal ring 58 and the whole being secured by pins 59. The felt disk or pad is centrally slotted at 60 to pass the connecting rod, and the parts are so proportioned that 75 the rear or bottom face of the piston at 61 contacts rather closely with the disk or pad at each stroke. The portion of the casing forward of the partition 19 is supplied with heavy grease to a level a little below the 80 crank shaft so that the crank pin dips into it at each stroke. In this way the grease works up and keeps the lower side of the felt pad coated so that the pad is heavily saturated, the grease working through to the upper side 85 in sufficient quantities to supply the necessary portion of grease to the piston at each stroke as it comes in contact with the disk.

The cylinder head in the form of the invention shown is outside the turret 10 which is open at the top, and this cylinder head has two valve chambers 62 and 63. In valve chamber 62 is a poppet valve 64 opening inward and serving as the intake valve, and in the valve chamber 63 is a valve 65 opening 90 outward and serving as the delivery valve. The valve chambers are each provided with plugs 66 by the removal of which the valves are made accessible for grinding and replacements. The cylinder head is also connected 95 to an intake passage 67 and a delivery 68, the latter leading to a separating and condensing chamber 69 which as shown is suitably supported on the outside of the casing by a bracket 70.

An important feature of the invention resides in the arrangement of the inlet valve 64, which as aforesaid, opens inwardly to prevent it from falling into the cylinder in case it becomes released as by displacement 100 or sheering of a valve pin 601. This arrangement consists in placing the valve and valve seat, the latter being indicated by reference characters 602, so that a small segment of the valve overlies the cylinder wall. 115 To provide sufficient play of the valve so that it may have the required opening the cylinder wall is notched as indicated at 603, the notch being of horizontal cross section slightly greater than the corresponding segment of the valve.

Looking at the casing from the rear as shown in Figure 5 and at the right in Figure 1, it will be noted that there is an opening 72 just above the rear crank shaft bearing 120 35. This opening is overhung by the depending plate or projection 73 on the top half of the casing, which plate extends almost across the casing from one side to the other of the rear, the opening 72 being cor- 125 130

respondingly shaped. This depending plate provides a downwardly disposed horizontally extending elongated opening for the admission of air.

5 In operation the rotary pump or blower 5 sets up a suction at the opening 30 to satisfy which, air in considerable volumes is drawn through the opening 72 under the depending plate 73. The draft thus created passes, 10 first, over the bearing 35 of the crank shaft, then over the bearing 46 at the rear end of the motor shaft, then around and through the motor housing and through the opening 34 around the crank shaft, whence it is 15 brought in contact with the front crank shaft bearing 20. From these points it is gathered at the opening 30 as described, passing through the fan 5 by which it is moved and caused thus to circulate, to the 20 turret 10 where it sweeps the entire outer wall of the pump cylinder and finally escapes by way of an opening 74, see Figure 1, provided for this purpose between the top edges of the turret and the top flange of the 25 cylinder.

In this connection it will be noted that there is a baffle or plate 75 separating the turret or cooling air exit passage from the crank case space to prevent the loss of lubricant which might splash up into the outgoing air draft and be thus carried over and out of the casing, as the baffle is preferably held between the edges of the two halves of the casing. For a similar purpose 30 the cylinder casting 2 is formed of depending flanges 76.

One of the important objects attained is the complete and efficient cooling of the parts which is brought about by their complete enclosure in a casing which acts as an air pocket and their arrangement as herein described and by the distribution of the air current just outlined, so that it is passed over the bearings through the motor and caused to thoroughly sweep the walls of the pump cylinder. The cooling of the parts, particularly the motor, is so efficient that the motor can be run at a high rate of speed and is therefore connected to the pump at a very low gear, giving the desired amount of power with a much smaller motor than has previously been used, particularly with the open systems.

The manner of supporting the different units within a single housing by bridging them across the lower half of the housing and covering them with the upper half, gives a cheap and efficient housing construction, a rigid support and an otherwise desirable arrangement. Also, the system of lubrication by which the heavy grease which cannot be carried into the air being pumped, is supplied in minute quantities with continuous regularity and uniformity to all the bearing surfaces, is of great advantage both

on account of its efficiency as a lubricant, its economy as to lubricating material, its permanency, and because it makes it possible to supply the machine with lubricant at one time for several months running, and further because it dispenses entirely with the presence of grease or oil in the compressed air.

We have thus described specifically and in detail a machine embodying our invention in the preferred form, but the specific description is supplied in order that the device may be easily understood and constructed by those skilled in the art, these terms being used in the descriptive rather than in a limiting sense, the scope of the invention being defined in the claims:

1. A pumping apparatus consisting of a pumping cylinder, a piston, a crank and a crank shaft, a motor, means connecting the motor to the pump crank shaft to drive the same, suitable bearings for said parts, a fan connected to said members to move therewith, a casing enclosing said members, the casing having an opening adjacent one end to admit air and having a transverse partition near said end with an aperture in which the motor is set, the fan being immediately in line with said opening beyond the motor, a turret in the casing open at one end, the pump cylinder being set in the turret with the opening encircling the cylinder near the head, the fan having the effect of drawing a current of air in at the opening at one end, passing it in contact with the bearings through the motor to the fan and delivering it so that it sweeps the pump cylinder, passing out through the openings at the end of the turret.

2. In a gas compressing and exhausting apparatus, the combination of a pump cylinder and piston, a motor, a shaft to which the motor is mounted, a fan on said shaft and a crank shaft for the pump, a casing enclosing the entire apparatus and having an elongated opening at one end, the motor and crank shaft having bearings immediately adjacent said opening, a transverse partition with an opening in which the motor is mounted, a transverse partition beyond the motor having an opening in line with the motor and fan, a turret surrounding the pump cylinder with an opening at the end of the turret conforming to the periphery of the cylinder near the head whereby the fan is caused to draw air in at the opening passing over the bearings through and around the motor, through the fan opening, delivering it around the pump cylinder, sweeping the entire surface of the cylinder and passing out through the opening at the end of the turret.

3. An air pumping and exhausting apparatus consisting of a pump, a motor, a cooling fan, gearing connecting the motor

and pump, a casing enclosing the entire apparatus, the same being formed in upper and lower sections, and supporting means by which the units of said apparatus are 5 mounted by bridging across the top of the lower section.

4. Air compressing apparatus consisting of a pump having a cylinder, a piston, a crank, a crank shaft, a motor having a shaft, 10 a fan thereon, gearing connecting said shafts which are parallel, a casing enclosing said apparatus, the same being elongated in the direction of the length of the shafts having an opening at one end adjacent the ends of 15 the shafts which have bearings at this end, means for causing the air current created by the fan to pass in the direction of the length of the shafts through and around the motor, the casing including a wall sur- 20 rounding the pump cylinder forming a jacket encircling the outer surface of the pump cylinder with an opening near the head so that the air is caused to pass around and sweep the surface of the pump cylinder and pass 25 through said opening.

5. In combination, a pump and motor, a casing enclosing the same, means for lubricating the pump consisting of a grease receptacle in the path of the crank pin, an 30 absorbent member in the path of the rear end of the piston, the latter having an opening for the passage of the connecting rod so that the absorbent member receives grease from the said receptacle, which grease, being 35 passed through the absorbent member, is transferred to the piston when the latter contacts with it, means for lubricating the pump shaft and the motor shaft, consisting of a grease receptacle on the pump shaft 40 bearing, the bearing having an opening leading from said receptacle to the bearing sur-

faces, a wick in said opening and means for pressing the same against the surface of the shaft, the motor shaft having a second bearing over the first-mentioned bearing with 45 an opening from below leading to the shaft surface, a wick in said opening leading from said latter receptacle, and means for pressing said wick against the surface of the shaft whereby the pump and bearings are lubri- 50 cated with nonfluid grease.

6. Means for lubricating a shaft bearing consisting of a cup on the bearing above the bearing, the cup having an opening leading to the shaft surface, the same having side 55 walls on a flat arc or angle, a wick in said opening conforming to said side walls and to the surface of the shaft exposed by said opening, and means in the form of a plate spring for pressing said wick against the 60 shaft, means for lubricating adjacent shaft bearings consisting of a cup on one said bearing, an opening in the bottom of said cup, a wick in said opening conforming to the said walls and to the surface of the shaft, 65 means for pressing said wick against the surface of the shaft, the remainder of the wick being in the cup, an opening in the other bearing leading to the shaft surface, the same having walls arranged on a shallow arc or 70 angle, a wick in said opening and a plate spring at one side pressing the wick against the shaft surface, the wick dipping into the cup on the aforementioned shaft.

Signed by us at Baltimore, Maryland, this 75
18th day of July, 1919.
